UNITED STATES PATENT OFFICE.

JOHN E. GATES, OF ROCHESTER, NEW YORK.

FRAME FOR LEATHER BAGS.

1,409,371.

Specification of Letters Patent. Patented Mar. 14, 1922.

Application filed January 27, 1921. Serial No. 440,463.

To all whom it may concern:

Be it known that I, JOHN E. GATES, a citizen of the United States, residing at Rochester, in the county of Monroe and State of New York, have invented certain new and useful Improvements in Frames for Leather Bags, of which the following is a specification.

The object of this invention is to provide a new and improved form of construction 10 of a metal frame for traveling bags, etc.

Another object of this invention is to provide a new method for covering the metal frame of a traveling bag, etc., and fastening 15 it to the bag proper.

These and other objects of this invention will be fully illustrated in the drawings, described in the specification and pointed out in the claims at the end thereof.

20 In the accompanying drawing:

Fig. 1 is a perspective view of the blank from which one side of the metal frame for the top of the bag is formed.

25 Fig. 2 is a perspective view of the blank from which the other side of the metal frame is formed.

Fig. 3 is a perspective view of the leather blank for covering both sides of the metal frame.

30 Fig. 4 is a perspective view of the leather blank of Fig. 3 and the blank for one side of the frame of Fig. 2, assembled.

Fig. 5 is a perspective view of the blank for the frame and the leather covering blank 35 therefor of Fig. 4, bent to the desired form.

Fig. 6 is a perspective view of one of the braces around which each half of the frame is formed and then fastened thereto.

Fig. 7 is a perspective view of a portion 40 of the traveling bag showing the frame, leather coverings and braces assembled and connected to the bag, the parts being broken away in section.

In the several figures of the drawings, like 45 reference numerals indicate like parts.

In the making of traveling bags, as it is practiced at the present time, the metal frame which encircles the top of the bag proper, is covered with leather after the 50 frame is bent and is then sewed thereon by hand and the bag proper is then sewed to the covering of the metal frame by hand. This is a very expensive operation in the making of traveling bags because of the fact that it

is a slow process and must necessarily be 55 done with great skill.

In my present invention, the making of the metal frame and the covering of it has been simplified so that the bag proper can be easily fastened thereto by machine. This 60 increases the speed with which a bag of this kind can be made and improves the appearance of the finished product.

As shown in the accompanying drawings, the metal frame is made up of a pair of 65 metal strips 1 and 2, each of which forms one half of the frame. The strip 1 is about one half the width of the strip 2 and has a pair of slots 3 and 4 formed near the top edge thereof, into which the latch of the bag 70 is adapted to engage. The middle of the strip 1 is slightly cut out to permit the mounting of the lock for the bag thereon. At each end, the strip 1 has an ear 5 formed thereon, which is perforated to receive the 75 pivot pin, with which the halves of the frame are fastened together. The metal strip 2 has its ends rounded and also perforated to receive the same pivot pins which hold the frame together in the middle. 80

Each of the strips 1 and 2 is provided with a series of lugs 6, 6 and 7, 7. These lugs are integral with the metal strips and are bent so as to project at right angles to the strip and be located on the inside of the frame 85 after it is bent into the desired shape. Each of the lugs is perforated so that the reinforcing strip or brace 8 can be securely fastened thereto. But before this is done, the metal strip is covered with leather, which is 90 done, using a leather strip 9 which has previously been cut to the desired size and perforated at intervals corresponding to the intervals at which the lugs 6 and 7 are formed on the metal strips 1 and 2. Each of the 95 metal strips is covered by passing the lugs thereof through the perforations in the leather strip and then folding the leather strip over the top of the metal strip and down on the other side thereof, as indicated 100 in dotted lines in Fig. 4.

After the metal strips have been covered in the manner above described, the reinforcing strip or brace 8 is fastened to the inside of the covered metal strip by riveting the 105 brace to some of the lugs 6, 6, and then bending the covered metal strip around the brace to conform to the outline thereof. All of

the brace is then riveted to the lugs on the metal strip, which has been formed around it so that the covered metal strip will permanently retain this bent form.

5 In covering each of the metal strips 1 and 2, the ears at the ends thereof are left exposed and after being bent into the rectangular form as above described, a pair of these frames are then fastened together by 10 suitable pivot pins that pass through the perforations in the ears of the metal frame. A complete frame is thus formed, which is hinged in the middle at each end so that it can be folded up to allow the narrower metal strip to telescope into the wider strip.

15 The frame, after being covered and formed in the manner above described, is then ready to have the bag proper fastened thereto. This is done by sewing the upper 20 edge of the bag to the outside of the covering of each of the metal strips below the line where the brace 8 is riveted thereto. The stitching together of the covering strip and the upper end of the bag is done by machine 25 and the stitches pass through the bag proper near the top edge and both the outer and inner end of the covering strip of the metal strips 1 and 2. The covering of the metal strips is thus not only held in place by the 30 lugs 6 and 7 but is also held thereon by sewing together the free ends at the bottom of the metal strips. The double thickness of the covering strip to which the bag proper is being sewed in turn gives the bag a strong 35 support on the frame as well as neat looking joint between the frame and the bag.

I claim:

1. In a metal frame for hand bags, etc., the combination of a pair of metal strips, a 40 leather strip folded over each of said metal strips, means on said metal strips to hold said leather strip in place thereon, and means to lock said leather strip in place on said first named means.

45 2. In a metal frame for hand bags, etc., the combination of a pair of metal strips, a leather strip folded over the top of each of said metal strips, means provided integral with said metal strips to engage said leather 50 strip and hold it in place on said metal strips, a second means attached to said first means to prevent the removal of said leather strip from said metal strip, the free ends of said leather strip being adapted to be sewed 55 to the bag proper below said metal strips.

3. In a metal frame for hand bags, etc., the combination of a pair of metal strips, a

leather covering for each of said strips, lugs on said metal strips adapted to engage into suitable perforations in said leather 60 strips, a bracing member attached to said lugs on said metal strips on the outside of said leather strip to hold said leather strip in place on said metal strips, and reinforce said metal strips.

4. In a frame for hand bags, etc., the combination of a metal strip, lugs provided at the lower edge of said metal strip and projecting out from said metal strip, a leather strip having perforations provided 70 therein corresponding to the number and spacing of said lugs, said lugs adapted to engage into the perforations of said leather strip, said leather strip being adapted to be folded over the top of said metal strip, a bracing strip fastened to said lugs, said metal strip being bent around said bracing strip, said bracing strip being adapted to hold said metal strip in a predetermined form and reinforce said metal strip.

5. In a frame for hand bags, etc., the combination of a pair of metal strips, lugs provided on the under side of said metal strips, ears having perforations therein formed at each end of said metal strips, a leather strip having perforations therein for each of said metal strips, said lugs on said metal strips being adapted to engage into the perforations in said leather strips, said leather strips being adapted to be folded over the top of 80 each of said metal strips to cover both sides thereof with the ears formed at each end of said metal strips exposed, a bracing strip fastened to said lugs outside of said leather strips to reinforce each of said metal strips 85 and hold them in a predetermined form, a pivot pin adapted to pass through a pair of oppositely located ears on said metal strips to make each of said leather covered strips swing on the other of said strips.

6. In a metal frame for hand bags, etc., the combination of a pair of metal strips, lugs bent up at the bottom of each of said strips and projecting from it at right angles thereto, a leather strip having perforations 105 therein adapted to fold over said metal strips with said lugs projecting through the perforations in said leather strips, a strip fastened to the ends of said lugs to fasten said leather strip to said metal strip and said 110 lugs formed thereon.

In testimony whereof I affix my signature.

JOHN E. GATES,
